(57) **CLAIM**

We claim the ornamental design for a model vehicle work stand assembly, as shown and described.

DESCRIPTION

FIG. 1 is an upper, left, front perspective view of a model vehicle work stand assembly showing our new design;

FIG. 2 is a front elevation view thereof;

FIG. 3 is a rear elevation view thereof;

FIG. 4 is an upper plan view thereof;

FIG. 5 is a lower plan view thereof;

FIG. 6 is a right side elevation view thereof;

FIG. 7 is a left side elevation view thereof;

FIG. 8 is an upper, right, rear perspective view thereof; and, FIG. 9 is a lower, left, front perspective view of the model vehicle work stand assembly.

In the drawings, the broken lines illustrate portions of the model vehicle work stand assembly that form no part of the claimed design.

1 Claim, 6 Drawing Sheets
